ELECTRIC STEAM IRON

Joseph H. Cone, Bridgeport, Conn., assignor to
Casco Products Corporation, Bridgeport, Conn.,
a corporation of Connecticut

Application April 23, 1951, Serial No. 222,381

14 Claims. (Cl. 38—77)

1

This invention relates to safety valve and tank filling and emptying means of steam irons, particularly those of the boiler type.

An object of the invention is to provide an improved steam iron wherein the tank or boiler may be very easily and quickly filled or completely emptied whenever desired.

Another object of the invention is to provide an improved boiler type steam iron characterized as above, incorporating safety valve means in conjunction with effective emptying means in a manner to obtain an extremely simple and reliable construction and one not likely to get out of order after extended use.

A further object of the invention is to provide a simple and easily installed unitary replacement part for existing boiler-type steam irons, comprising a combined steam dome, emptying valve and safety valve whereby the operation and performance of said existing irons may be simply and economically improved.

Still another object of the invention is to provide a steam iron according to the foregoing, having improved and simplified stopper means for the filler opening, to minimize the likelihood of spluttering when filling a hot iron and to reduce the cost of the stopper.

A still further object of the invention is to provide in a steam iron of the above type improved and simplified indicator means, in conjunction with the filler means, to apprise a user that the boiler is full during the filling operation.

In accomplishing the above objects I provide a novel iron structure comprising, in the embodiment of the invention herein illustrated, a boiler having separate and distinct water filling and emptying means. Preferably the emptying means is associated with the steam dome of the iron to provide a unitary assemblage and to simplify the structure and avoid duplication of parts as will be later brought out in detail. In carrying this out I provide a discharge opening in the top of the steam dome, and a novel stopper assembly for sealing and unsealing said discharge opening. The stopper assembly is held captive by the steam dome and is so arranged that it remains in either a sealing position or an unsealing position, being maintained therein by yieldable means and being readily shiftable manually between said positions. When in unsealing position, the stopper permits water to flow out of the steam dome should the boiler be turned upside down, and by virtue of the discharge orifice being in the top of the dome, practically all of the content of the boiler may be easily and quickly emptied. When in sealing

2

position the stopper may be unseated by excessive steam pressure, thus enabling it to act as a safety valve. In addition, the yieldable means of the stopper assembly operates to move the stopper to sealing position if, when it is in unsealing position, it is shifted toward sealing position a predetermined extent, thus enabling an automatic closing of the stopper to be effected if the iron is of the type illustrated herein, having a hinged handle which is swung back to expose the filling and emptying means.

By providing a steam dome which is readily demountable, and by incorporating the emptying and safety valve means in the steam dome I am enabled to provide an advantageous unitary replacement unit for existing steam irons, comprising a combined steam dome, emptying valve and safety valve. Accordingly a deficiency of present irons with single-purpose steam domes, i. e. the difficulty of completely emptying the boiler, may be quickly, simply and economically corrected by a mere exchange of parts.

I also provide a novel stopper for the filler opening which is of simplified construction, comprising merely a closure member having a hollow, apertured mounting barrel movably carried in the filler opening to position the closure in sealing or unsealing positions. The closure may be readily raised or lowered manually when the handle of the iron is in swing-back position, and for the raised position of the stopper the apertures and structure of the barrel and stopper function to minimize spluttering if the boiler is filled when the iron is heated.

Other features and advantages will hereinafter appear.

In the accompanying drawings:

Figure 1 is a side view partly in elevation and partly in vertical section of a hinged handle type steam iron embodying the invention.

Fig. 2 is a fragmentary vertical sectional view of the steam dome and safety valve portion of the iron and associated structure, showing the safety valve in blow-off position.

Fig. 3 is a side view partly in section and partly in elevation of the iron with the handle raised, and with the stopper for the steam dome in unseated position for emptying the boiler.

Fig. 4 is an enlarged vertical sectional view of the steam dome and stopper means associated therewith.

Fig. 5 is a separate detail, partly in elevation and partly in vertical section, showing the filler opening and stopper therefor, with the stopper in unsealing position.

Fig. 6 is a view like Fig. 5 but showing a modi-

fied form of stopper, provided with indicator means.

Referring to Figs. 1 and 3, the improved steam iron of this invention comprises a sole plate 20 mounting a boiler 21 and casing 22.

Pivotal secured to the casing 22 at its rear is a handle structure 23 comprising a generally flat base portion 24, front and rear upright posts 25 and 26 and a handle proper 27. The front post 25 of the handle structure is made hollow, having a recess 28 to clear an upright tapered thimble or steam dome 29 secured to the forward upper portion of the boiler 21. Within the dome 29 a steam pipe 30 is disposed, leading to a steam chamber 20a in the sole plate 20, which in turn communicates with vent holes 20b in the sole plate. Baffles 31 are arranged around the steam pipe 30 to minimize the likelihood of water splashing into the pipe.

In accordance with the present invention the boiler 21 is provided with a filler opening 32 and a separate water discharge opening 33, the latter being in the top of the steam dome 29. At the filler opening 32 a funnel 34 is mounted, carried on the top wall portion of the boiler and extending downward. Novel and simplified anti-splutter stopper means are provided for the filler opening 32, enabling the boiler 20 to be easily and quickly filled even when the iron is hot. This stopper means comprises a sealing ring 35 of rubber-like or gasket material, carried at the end of a hollow stem or barrel 36 having elongate openings 37 in its walls, said stem being axially movable in a cylindrical bottom portion 34a of the funnel 34. The bottom of the stem 36 has a flange 38 providing a stop when the stem is raised, and the top of the stem is outwardly flanged and has press-fitted to it a tapered handle 39 terminating in a knob 40. Detent nibs 36a are provided on the walls of the barrel 36 and said walls are made resilient whereby the nibs may be forced through the funnel portion 34a to yieldably hold the stopper in raised or lowered positions. In Fig. 1 the stem 36 and stopper 35 are lowered whereby the opening 32 is sealed. If it should be desired to fill the boiler 21, the handle structure 23 is raised, and the stopper 35 and stem 36 raised by the knob 40, whereupon water may be introduced into the funnel to flow to the boiler. When the water rises into the bottom of the funnel 34 it will indicate that the boiler is full, whereupon the stopper may be pressed down and the excess water if any poured from the funnel by tilting the iron. During the filling of the boiler through the funnel 34, air will be vented from the boiler through the steam pipe 30 and discharge openings 20a in the sole plate. Also, air may be vented through the top areas of the openings 37 in the stem 36. Preferably the base 24 of the handle structure 23 is provided with a depending projection 41 arranged to engage the knob 40 and depress the stopper 35 to sealing position when the handle structure 23 is swung down from the position of Fig. 3 with the stopper raised. The provision of the relatively large, elongate openings 37 in conjunction with the obstructing effect of the handle 39 and knob 40 result in a minimum of spluttering if the boiler should be filled while the iron is hot. The reason for this is that water and steam which may be forced up through the filler opening will strike the underside of the handle 39 and have their force dissipated, while vapors are permitted to escape in generally lateral directions through the upper portions of the openings 37.

For the purpose of latching the handle structure 23 in the closed or operative position shown in Fig. 1, a latch mechanism is provided comprising a knob 44 carried on a shaft 45 passing through the base 24 of the handle structure. The lower end of the shaft has a crosshead 46 passing through a slot 47 in a latch plate 48 secured to the casing 22. When the crosshead 46 extends transversely of the slot 47 the latch is operative to hold the handle structure in the closed position of Fig. 1. When the knob 44 is turned to extend the crosshead 46 longitudinally of the slot 47 the latch releases the handle structure 23 and the latter may be swung upward to the filling position shown in Fig. 3.

In accordance with the present invention novel manually operable stopper means are provided on the steam dome 29, functioning for the purpose of emptying the boiler when the iron is inverted and also as a safety valve during operation of the iron. In this connection it will be noted that the tapered shape of the dome 29 enables it to function as a spout when the iron is being emptied. By the provision of the stopper means on the dome, and by making the dome readily demountable I obtain a desirable and advantageous unitary replacement assemblage for a steam iron whereby its operation and performance can be appreciably improved, as will be brought out shortly.

Referring to Fig. 4, this closure structure comprises a barrel 49 slidable longitudinally in the discharge opening 33 of the steam dome 29. At its lower end the barrel 49 is flared outward, providing a flange 50 which acts as a guide by engagement with the inside of the steam dome. The flange 50 also engages one end of a helical compression spring 51 the other end of which engages the underside of the top of the steam dome. The upper end of the barrel 49 carries a sealing washer 52 which may be of rubber or rubber-like material, said washer being held in a flanged disk 53. The side walls of the barrel 49 are provided with discharge openings 54. It will be observed that the spring 51 normally yieldably holds the washer 52 in engagement with the top of the steam dome 29 whereby the discharge opening thereof is sealed. To oppose the action of the spring 51 I provide a lanced finger 55 in the wall of the barrel 49, having a rounded or bulbous end portion 56 adapted to engage the edge of the discharge opening 33 of the steam dome. The finger 55 is so adjusted that it will maintain the stopper washer 52 and barrel 49 in raised or emptying position as shown in Fig. 3 in consequence of the washer being manually lifted to said position. The finger 55 thus acts as a spring detent. If the washer 52 should be depressed a predetermined amount, by nib 25a in the post 25 when the handle swings down, causing the bulbous portion 56 of the finger to pass the edge of the discharge opening 33, then the spring 51 will operate to complete the downward movement of the washer and maintain the latter in sealing engagement with the top of the steam dome 23. The spring 51 is of a strength to enable excess steam pressure to lift the washer 52 off of the seat of the steam dome opening whereby steam may be discharged into the recess 28 of the front handle post 25, and be thereby dissipated. Accordingly the stopper structure shown in Fig. 4 functions as an efficient and effective safety valve when the iron is being used. In Fig. 2 the washer 52 is shown as being raised by excess steam pressure, enabling the steam to be dis-

5

charged into the hollow post of the handle. As shown in Fig. 4 the inside of the base portion of the steam dome 29 is provided with screw threads accommodating a threaded nipple 21a of the boiler and casing, and the walls of the steam dome are made hexagonal as at 29a to accommodate a wrench whereby the dome and valve assemblage may be readily demounted, or used to replace a single purpose steam dome in existing irons. Thus the combined steam dome, emptying valve and safety valve assemblage may be produced as a single replacement unit, and when such unit is substituted for the steam dome on an existing steam iron it will provide for quick and easy complete emptying of the boiler, and provide a reliable safety valve action. In connection with this latter it will be noted that operation of the valve to empty the iron will disclose or correct any tendency to stickiness which might impair its functioning in the important role of a safety valve.

Operation is as follows:

When it is desired to fill the boiler 21 the operator merely releases the latch for the handle and raises the handle structure to the position of Fig. 3. He may if he desires lift the washer 52 to the raised position shown in Fig. 4, venting the boiler 21 through the steam dome. However, this is not essential as the boiler would normally be vented through the steam discharge openings 20b in the sole plate 20. The operator then pours water into the funnel 34 of the filler opening 32. By virtue of the air being vented as above set forth, water will enter the boiler through the funnel 34 without bubbling or splattering, and quickly fill the boiler. Even if the iron is hot, the tendency for the water to splatter or be thrown up or back will be minimized by the stopper construction, as already explained.

When it is desired to empty the boiler, the user merely inverts the iron with the handle structure 23 in raised position and with the stopper 52 raised. Water will run out of the boiler through the steam dome opening, and due to the crowned shape of the boiler top and the high position of the steam dome, substantially all of the water will flow from the boiler.

For the purpose of providing a more stable control of the iron body when the handle structure 23 is in raised position a latch mechanism 56 may be provided in conjunction with the hinge means at the rear of the boiler casing 22. Such latch mechanism 56 may include a manually operable release knob 57, and may operate to automatically latch the handle in raised position, and to release the handle when the knob 57 is shifted. Details of one type of latch mechanism may be had by referring to my copending application, Serial No. 128,270, filed November 19, 1949 entitled "Steam and Dry Flatiron."

A modification of the invention is shown in Fig. 6, wherein the stopper for the filler opening is provided with indicator means to show when the boiler is properly filled. This indicator means comprises a float in the form of a ball 58 carried within a barrel 36b slidably mounted in a funnel 34b. The barrel 36b carries a sealing annulus 35 and handle 40 as previously described, but differs from the barrel 36 in that its lower end 36c is flanged or extended inward to hold the ball 58 captive in the barrel. Intermediate its ends the barrel 36b has a crimp 36d acting as a stop, and detent nibs 36e are disposed near the top of the barrel for engagement with the walls of the opening in the funnel 34b.

6

When the stopper and barrel are in raised position, illustrated in Fig. 6, the water level in the boiler will be indicated by the float 58, apprising a user of the filled condition of the boiler.

5 Variations and modifications may be made within the scope of the claims and portions of the improvements may be used without others.

I claim:

1. As a new article of manufacture, a unitary, combined steam dome, emptying valve and safety valve for a steam iron, comprising a thimble having a discharge opening in its top, and having means on its base for securing it to a boiler; a stopper for the discharge opening; means mounting the stopper on the thimble for movement between sealing and discharging positions; means yieldably holding the stopper in sealing position, said means yielding in response to excess steam pressure on the stopper to unseat the latter and relieve said steam pressure; and cooperating means on the valve mounting means and thimble for holding the valve in discharge position.

2. The invention as defined in claim 1, in which the stopper mounting means comprises a barrel passing through and slidably axially in the opening of the thimble, said barrel having discharge openings in its walls, and in which the yielding means comprises a spring carried on the barrel.

3. As a new article of manufacture, a unitary, combined steam dome, emptying valve and safety valve for a steam iron, comprising a thimble having a discharge opening in its top, and having mounting means on its base; a stopper for the discharge opening; means mounting the stopper on the thimble for movement between sealing and discharge positions; and cooperating means on the thimble and stopper mounting means yieldably holding the stopper in either of said positions in which it is placed.

4. As a new article of manufacture, a unitary, combined steam dome, emptying valve and safety valve for a steam iron, comprising a thimble formed of drawn sheet metal with hexagonal walls, said thimble having a discharge opening in its top, and having an outwardly flanged base provided with internal screw threads; a stopper for the discharge opening; means mounting the stopper on the thimble for movement between sealing and discharge positions; and means yieldably holding the stopper in either of said positions in which it is placed, said means including a resilient finger carried by the mounting means for the stopper, engageable with an edge portion of the thimble at the discharge opening thereof when in discharge position.

5. In a steam iron, a boiler having a water discharge opening; a stopper for the discharge opening; means mounting the stopper on the boiler for movement between sealing and discharge positions, said means including a barrel extending through said discharge opening and movable axially therein, and said barrel having discharge openings in its walls; and means yieldably holding the stopper in either of said positions in which it is placed, including a compression spring carried by the barrel and including a resilient finger lanced from the wall of the barrel in position to engage with an edge of the discharge opening when the barrel is in discharge position.

6. In a steam iron, a boiler having a water opening; a stopper for said opening; a handle for the iron, mounted on the iron for movement between an operative position adjacent the boiler and a position remote from the boiler to expose said stopper; means mounting the stopper on the

boiler for movement between positions sealing or unsealing the water opening; means yieldably holding said stopper in either of said positions in which it is placed, including means for moving the stopper to sealing position when it is shifted a predetermined extent toward said position from the unsealing position; and means responsive to movement of the handle from its remote to its adjacent position, for automatically moving the stopper said extent toward its sealing position when it is in unsealing position, thereby to seal the opening whenever the handle is in operative position.

7. In a steam iron, a boiler having an opening in its top portion; safety valve means on the boiler, comprising a stopper for said opening; means passing through said opening, mounting the stopper for movement between seated and unseated positions; means yieldably holding the stopper in seated position, said means yielding in response to excess steam pressure in the boiler to relieve said pressure; and a shield movably mounted on the iron and normally fixed in position overlying said stopper to prevent steam from discharging upward when the stopper is unseated to relieve steam pressure.

8. The invention as defined in claim 7, in which there is a handle structure pivotally mounted on the iron, and in which the shield means comprises a hollow post of said handle structure.

9. A steam iron comprising a water tank; filling means for the tank including a filling orifice; closure means for said orifice, said tank having another orifice above the normal level of the water in the tank, through which air in the tank can escape while the tank is being filled through said filling orifice; closure means for the second-named orifice, carried by the tank for movement between open and closed positions; and means including a manually-operable member for shifting both said closure means to closed positions, said member comprising an ironing handle for manipulating the iron, hingedly mounted on the iron for closure-actuating movement from an inoperative position swung away from the tank to an operative position disposed over the tank.

10. A steam iron comprising a water tank having filling means in an upper portion, including an orifice, and having an air vent in said portion, spaced from the orifice; a closure for said orifice; a closure for said air vent, carried by the tank for movement between open and closed positions; and means including a manually operable member movable with respect to the tank, for moving the closures against the orifice and vent with a single movement of said member.

11. In a steam iron, a tank having an opening for the passage of fluid; a stopper for said opening; a handle for manipulating the iron, mounted on the iron for movement between an operative position adjacent the tank and a position remote from the tank; means mounting the stopper on the tank for movement between positions sealing and unsealing the water opening thereof; means yieldably holding the stopper in either of said positions in which it is placed; and means for overcoming said yieldable holding means and shifting the stopper from unsealing to sealing positions in response to movement of the handle from its remote to its operative position.

12. As a new article of manufacture, a unitary, combined steam dome, emptying valve and safety

valve comprising a thimble having a water discharge opening at the top thereof; a barrel extending through said discharge opening and movable axially of the thimble, a stopper comprising a flanged disk having a sealing washer therein connected to the end of the barrel to engage and seal the opening in the thimble, said barrel being movable between sealing and discharge positions and having discharge openings in its walls adjacent the stopper; and means yieldably holding the stopper in either of said positions in which it is placed, including a compression spring carried by the barrel and a resilient finger lanced from the wall of the barrel in position to engage with an edge of the discharge opening in the thimble when the barrel is in discharge position.

13. As a new article of manufacture, a unitary, combined steam dome, emptying valve and safety valve comprising a thimble having a water discharge opening at the top thereof; a stopper for the discharge opening; means mounting the stopper on the thimble for movement between sealing and discharge positions, said means including a barrel extending through said discharge opening of the thimble and movable axially of the thimble and said barrel having discharge openings in its walls adjacent the stopper; and means yieldably holding the stopper in either of said positions in which it is placed, including a compression spring carried by the barrel and a resilient finger lanced from the wall of the barrel below the top of the discharge openings in the barrel and in position to engage with an edge of the discharge opening of the thimble when the barrel is in discharge position, said compression spring yielding in response to excess pressure to unseat the stopper and move the barrel through the discharge opening in the thimble sufficiently to expose the discharge openings in the barrel to relieve the excess pressure without moving the resilient finger into holding position whereby said valve automatically recloses upon relief of said excess pressure.

14. A steam iron comprising a boiler having a filling opening; means extending around the filling opening and into the boiler, providing a water passage into the tank, said means extending below the top of the boiler and preventing complete emptying of the boiler through said filling opening, said boiler having an emptying opening spaced from the filler opening and located at its uppermost portion in unobstructed communication with every part of the boiler when the steam iron is inverted whereby the boiler may be completely drained of water through said emptying opening; a valve seat around said emptying opening; and a valve mounted on the boiler for controlled movement between an open position clear of the valve seat and a closed position on the seat.
